UNITED STATES PATENT OFFICE.

EDMUND A. SCHADE, OF NEW BRITAIN, CONNECTICUT, ASSIGNOR TO THE STANLEY WORKS, OF NEW BRITAIN, CONNECTICUT, A CORPORATION OF CONNECTICUT.

ROOFING BRACKET.

Application filed January 23, 1926. Serial No. 83,368.

This invention relates to brackets for use in laying pitched roofs to support the workmen and prevent them from slipping off the roof.

5 The aim of the invention is to provide a device of this sort having various features of novelty and advantage and which is particularly characterized by its extreme simplicity and strength in construction, its economy in 10 manufacture, and the ease and facility with which it may be secured and removed from position and moved from place to place.

In accordance with this invention, my improved roofing bracket is formed from strip 15 metal, the parts of which are bent to shape and riveted together, and the parts being so arranged and constructed that while the structure is relatively light, the bracket is rigid and sufficiently strong to stand the 20 strains to which it is subjected when in use.

Other objects of the invention will be in part obvious and in part pointed out more in detail hereinafter.

The invention accordingly consists in the 25 features of construction, combination of elements and arrangement of parts which will be exemplified in the construction herein-after set forth, and the scope of the application of which will be indicated in the appended claims.

In the accompanying drawings, wherein I have shown for illustrative purposes one of the many embodiments which the present invention may take:

35 Fig. 1 is a side view of my roofing bracket applied to a roof shown in cross section;

Fig. 2 is a top plan view of the bracket looking in the direction of arrow A, of Fig. 40 1; and

Fig. 3 is a sectional view taken on a line 3—3 of Fig. 1, and looking in the direction of the arrow.

Referring to the drawing in detail, my improved bracket is provided with a forwardly extending tang 10 having at its forward end means for hooking the same about a nail or tack C employed for securing in place the roofing elements D, such as shingles, or roofing strips. Extending outwardly from and preferably formed integrally with the lower end of the tang, is a shelf 11, the outer end of which is bent upwardly as of 12 and then over and inwardly as at 13 so to provide a 55 hooked portion for preventing lateral dis-

placement of a board or strip 14 positioned on the shelf. It is understood, of course, that the board 14 will be supported by two or more of my improved brackets and that the workman will stand on this board or lay 60 full length on the roof with his feet on the board. The board may also be used to support a ready supply of roofing elements. My improved bracket further includes a brace for this shelf. This brace may be 65 formed of one or more strips of metal suitably bent to shape. In the present instance the brace comprises two strips and has a roof engaging portion 17 secured to the shelf 11, and one or more struts 18, the opposite 70 ends of which are respectively secured to the shelf and the portion 17. In the present illustrative disclosure, two such struts are illustrated. The roofing engaging portion 17 has its forward end turned outwardly 75 as at 20 and this outwardly turned end is secured to the shelf by a rivet 21 or the like. The lower or rear end of the portion 17 is

turned upwardly and forwardly into the 80 form of a hook 22, the purpose of this hook being to provide an anvil, so to speak, which may be given a blow when it is desired to disengage the tank from the nail or tack over which it is hooked. The struts 18 are preferably formed from a single strip of metal, 85 one end of the strip being turned inwardly as at 23 and secured to the shelf by a rivet 24. The other end of the strip, which forms the upper end of the outer strut, engages the portion 12 of the shelf and is secured thereto by a rivet 25. Between the struts is a portion 27 which overlies the portion 17 and is secured thereto by rivets 28 and 29. In order to hold the brace in an upright position and to prevent lateral swaying of the support, there is secured to the portion 17, a lateral extending strip 33, the ends of which constitute feet adapted to engage the roofing element with which the portion 17 is an engagement. This strip is preferably secured in place by the rivet 29.

The forward end of the tang 10 is beveled as at 35 to facilitate insertion of the tang beneath roofing elements which have already been laid. The tang is provided with spaced 105 slots 36 which extend inwardly and forwardly from one edge of the tang.

From the foregoing description, taken in connection with the accompanying drawings, it will be seen that my improved roofing 110

2

bracket comprises a relatively few number of parts, each of which is formed of strip metal. The bends in these strips may be readily effected and the parts are easily assembled. The brace effectively prevents bending or distortion of the shelf, and the brace, itself, is so constructed and secured to the shelf that it will retain its shape altho it is subjected to extremely rough usage.

10 To remove the bracket from place, it is merely necessary to strike with a hammer or other tool, the lower end of the hook 22, thereby forcing the tang forwardly and as the slots 36 are inclined in the manner described, the tang will be cammed out of engagement with nail C over which it is hooked. The bracket can then be slid downwardly to withdraw the tang from beneath the roofing element, then the support is moved to a position higher up on the roof, and the beveled end of the tang is inserted beneath a roofing element to a position where one of the slots may again receive a nail or tack. After the roofing support has been removed from one position, the nail which has been employed as an anchor for the bracket, may be driven home by striking the roofing element which overlies the head of the nail.

30 It is, of course, obvious that my invention is susceptible of various modifications and

changes, and that the present disclosure is by way of illustration only and it is not to be taken as restrictive.

I claim as my invention:

1. A roofing bracket of the character described having a forwardly extending tang provided with means for anchoring the same, a shelf extending outwardly from said tang, and a brace for said shelf having a roof engaging portion and a strut between the roof engaging portion and shelf, the rear end of said roof engaging portion extending beyond said strut and being hooked to provide an anvil which may be struck when disengaging the tang from the member to which it is anchored.

2. A roofing bracket of the character described formed of strip metal and having a forwardly extending tang provided with means for anchoring the same, a shelf extending outwardly from, and formed integrally with, the rear end of said tang, and a brace having a roof engaging portion connected at its forward end to said shelf and a pair of struts formed of a single strip of metal and connected at their forward ends to said shelf, the intermediate portion of said strip being connected to said roof engaging portion.

EDMUND A. SCHADE.
